POSITION ADJUSTING DEVICE FOR
FURNITURE OR THE LIKE

Philip Billet and Irving Levy, New York, N. Y.

Application December 30, 1949, Serial No. 135,976

4 Claims. (Cl. 5—75)

1

This invention relates generally to position adjusting devices for relatively displaceable parts, and more particularly for articles of furniture, or the like, wherein it is desired to swingably raise and lower one part thereof relative to another part thereof, and more specifically to mechanism for maintaining the swingable part in a desired inclined position intermediate extreme upper and lower positions. This invention is particularly adapted for use in connection with couches, sofas, beds, seats brackets, chairs, physicians' or other tables, or the like.

An object of this invention is to provide a position adjusting mechanism.

Another object of this invention is to provide a position adjusting mechanism for a swingable part of an article of furniture, and for securing the swingable part at any angular position intermediate extreme upper and lower positions thereof.

A further object of the present invention is to provide, in an article of furniture, or the like, having one part thereof adapted to be swung to an inclined position relative to another fixed part thereof, mechanism for maintaining the swingable part in a desired inclined position intermediate extreme upper and lower positions; the mechanism including a pair of longitudinally telescoping members pivotally secured at the opposite ends thereof to the swingable and fixed parts of the article of furniture, and means in said members automatically maintaining the members in extended position to thereby prevent lowering of the swingable part after the latter has been raised to a position intermediate the extreme upper and lower positions thereof.

Still another object of this invention is to provide an adjustable supporting device for a swingable part of an article of furniture wherein the swingable part must first be raised to the extreme upper position and then depressed to the extreme lower position before the swingable part may be adjusted and maintained in a desired intermediate position.

With the foregoing and other objects in view, which will appear as the description proceeds, the invention resides in the combination and arrangement of parts and in the details of construction hereinafter described and claimed, it being understood that various changes and modifications may be resorted to without departing from the spirit or scope of the invention as defined in the claims, and without sacrificing the advantages thereof.

In the drawings:

Figure 1 is a side elevation of an article of furniture having a swingable part and including a position adjusting device therefor, with the

2

swingable part shown in depressed or extreme lower position;

Figure 2 is a view similar to that in Figure 1, with the swingable part shown in elevated or raised position;

Figure 3 is a side elevational view of a position adjusting device constructed according to this invention in a position just before extreme lower position;

Figure 4 is a front elevational view of the position adjusting device in the position illustrated in Fig. 3;

Figure 5 is a side elevational view of the position adjusting device in the position shown in Figure 3, but viewing the opposite side of the device;

Figure 6 is a rear elevational view of the position adjusting device in the position illustrated in Figure 3;

Figure 7 is a front elevational view of the position adjusting device in extreme depressed or lowered position;

Figure 8 is a front elevational view, showing the position adjusting device in extreme elevated or raised position;

Figure 9 is an exploded view of the several elements comprising the position adjusting device;

Figure 10 is a fragmentary vertical sectional view taken on the line 10—10 of Figure 8;

Figure 11 is a fragmentary front elevational view, partly broken away, showing the braking elements positioned within the position adjusting device;

Figure 12 is a plan view of a spring element forming a part of the device; and

Figure 13 is a horizontal sectional view taken on the line 13—13 of Figure 8.

Referring to the drawings, wherein like reference characters indicate like parts, a couch 10 is illustrated in Figures 1 and 2 and embodies a position adjusting device constructed according to this invention. While the invention is shown incorporated in a couch, it should be understood that it is adapted to use with any article of furniture, or the like, having relatively movable parts.

The couch 10 includes a fixed portion 11 supported upon the leg members 12. A head rest 13 is pivotally mounted adjacent the head end of the fixed portion 11 by the pins 14. In Figure 1, the head rest 13 is shown in the depressed or extreme lower position. In Figure 2, the head rest 13 is shown at an intermediate inclined position relative to the fixed portion 11. The head rest 13 is supported in the position illustrated by Figure 2 by the position adjusting device, generally indicated by the reference numeral 15, which is interposed between the movable sup-

port 16, forming part of the head rest 13, and the fixed support 17, forming part of the fixed portion 11.

The position adjusting device 15, the elements of which are shown in the exploded view of Figure 9, includes an elongated channel member 18 having a hinge plate 19 secured to the back surface at the top end thereof by the fastenings 20 which may be spot welding, bolts, rivets, or any other like securing means. A complementary hinge plate 21 is pivotally connected to the plate 19 by the hinge pin 22, and is secured to the movable support 16 by the screws 23, shown in Figures 8 and 10.

A flexible brake band 24, preferably formed of resilient metal, is disposed within the channel 18 and extends along the length of the latter. The band 24 has the opposite ends thereof secured by spot-welding, or the like, to the opposite side walls 25 and 26 of the channel 18, as at 27.

The channel 18 includes the inwardly directed flanges 28 and 29 extending along the forward edges of the side walls 25 and 26 respectively, as seen in Figures 11 and 13. The oppositely disposed wedge shaped brake members, or shoes, 30 and 31 are slidably disposed within the channel 18 on opposite sides of the band 24, and are formed to be capable of slight lateral play and retained within the channel by the overlying flanges 28 and 29. The brake shoes 30 and 31 are formed with bosses 32 and 33, respectively, extending outwardly between the inner edges of the flanges 28 and 29.

A resilient spring member 34 is bent to provide loops 35 and 36 at the opposite ends thereof, which loops engage over the bosses 32 and 33 respectively and urge the shoes 30 and 31 longitudinally together. The spring 34 will urge the confronting inclined surfaces of the shoes 30 and 31 against the opposite sides of the band 24, and will also urge the shoes 30 and 31 laterally into frictional engagement with the side walls 25 and 26 respectively of the channel 18. An elongated spring retaining plate 37 is formed with elongated slots 38 and 39 adjacent the opposite ends thereof, and is positioned on top of the spring 34 with the bosses 32 and 33 loosely extending through the slots 38 and 39.

A second relatively short channel member 40 includes a web 41 and right angularly disposed side flanges 42 and 43 extending along the longitudinal edges thereof. The lower end of the web 41 is looped in a direction opposite to that of the side flanges to form a portion 44 of a hinge pivot. A hinge plate 45 is pivotally connected to the portion 44 by a hinge pin 46 extending therethrough. The hinge plate 45 is provided with the openings 47 through which fastening screws 48 extend for connection to the fixed support 17, as seen in Figure 8. The channel member 40 is slidably disposed upon the channel member 18 with the web 41 of the former overlying the flanges 28 and 29 of the latter, and with the flanges 42 and 43 of channel 41 extending adjacent to the side walls 25 and 26 of the channel 18.

Inwardly directed tabs 49 and 50 are formed on the flanges 42 and 43, adjacent the lower ends thereof, as seen in Figure 6, and overlie the back of the channel 18 for preventing lateral displacement of the bottom portion of the channel 40 relative to the channel 18.

The web 41, of channel 40, is provided with an enlarged opening 51 through which the boss 32 of brake shoe 30 loosely extends so that the shoe 30 is movable relative to the channel member 40.

The web 41 is also formed with a relatively small opening 52 receiving the boss 33 of the brake shoe 31. The engagement between the opening 52 and the boss 33 is relatively close, so that, the brake shoe 31 is not movable with respect to the channel 40.

A cam member 53, having an opening 54 for receiving the boss 32, is rockably mounted upon the latter against the web 41. The boss 32 is formed with a threaded bore 55 threadably receiving the headed fastening member 56 for securing the cam member 53 thereto. The cam member 53 is formed with an inclined cam surface 57 for engagement in one position with the struck out lug 58 formed on the web 41 of the channel 40. A laterally bent arm 59 extends from a side edge of the cam member 53 parallel to the side flange 42 of the channel 40.

A plate 60, having an off-set laterally extending stop member 61, is secured to the central part of the back face of the channel 18, at the lower portion of the latter, by spot welding 62, or the like. The portion of plate 60 secured to channel 18 has a width which is substantially smaller than the gap between the tabs 49 and 50 provided on the channel 40 for embracing the channel 18, as seen in Fig. 13. Further, the stop member 61 is offset from the portion of the plate 60 secured to the channel 18 by a distance which is greater than the thickness of the tabs 49 and 50. Thus, as the channel 18 slides within the channel 40, the plate 60 and stop member 61 clear the tabs 49 and 50 and the latter do not interfere with such relative movement of the channels.

In operation, the hinge plates 21 and 45 are secured to the movable and fixed supports 16 and 17, respectively. The swingable part 13 of the article of furniture is then moved upwardly which will result in upward movement of the channel 18 relative to the channel 40. The brake member or shoe 31 will be held by the channel 40 which will cause the shoes 31 and 30 to separate, since the connection therebetween is by the spring member 34, and the shoe 30, frictionally engaging the channel 18, will tend to move upwardly with the latter. The separation of the brake shoes will result in relaxation of the frictional engagement of these members with the band 24 and the sides 25 and 26 of the channel 18, thus permitting the raising movement of the portions 13 of the couch.

When the lower extreme portion of the channel 18 has been moved into the channel 40, brought about by the head rest 13 being raised to the extreme upper position or extension Aa, the stop member 61 will engage the arm 59 of the cam member 53 and rock the latter to engage the cam surface or edge 57 with the projection 58 on the channel 40, as seen in Figure 8. Such engagement will support the wedge 30 and hold the latter away from the wedge 31 to thereby permit the movement of the channel 18 relative to the channel 40 in either direction, that is, either upwardly or downwardly. In this condition, the position adjusting device 15 will not support the head rest 13.

In order to place the device in operative condition, the headrest 13 is lowered to the extreme lower position shown in Figure 7. Figures 3-6 show the position of the cam member 53 at the instant contact is effected between the arm 59 of the cam member and the lower edge of the hinge plate 19 fixed to the channel 18. When the head rest is in extreme lower position, see

Figure 7, the distance between the hinge plates 21 and 45 will be reduced to the dimension A and the hinge plate 19 will rock the arm 59 and the cam member 53 for disengaging the cam edge 57 from the projection 58. When the cam 53 is free of the projection 58, the spring 34 will urge the brake shoes 30 and 31 together into braking position.

In this latter condition, the channel 18 may still be moved upwardly relative to channel 40, that is, the head rest may be raised. However, when the head rest is raised to an intermediate position, such as that shown in Figure 2, the position adjusting device 15 will prevent any downward swinging of the head rest from that selected position. Downward pressure upon the head rest 13 will only tend to wedge the brake shoes 30 and 31 more securely against the band 24 and the side walls 25 and 26. Having once selected an intermediate position, adjustment to a lower intermediate position can only be achieved by first raising the head rest to the upper extreme position to engage the stops 61 against the arm 59 for rocking the cam member 53 to brake releasing position, as described above, then lowering the head rest to lower extreme position for once again setting the brake shoes, and finally raising the head rest to the desired degree of inclination.

Having thus described and illustrated an embodiment of our invention, what is claimed as new and desired to be secured by Letters Patent is:

1. A position adjusting device for relatively movable parts comprising an elongated channel member, a receiving member slidably receiving said channel member, an elongated brake band disposed in said channel member with the opposite ends of said band secured to the latter, a pair of oppositely disposed wedge shaped brake members in said channel member with said band positioned between the confronting faces of said brake members, one of said brake members being fixed relative to said receiving member, spring means connecting said pair of brake members and adapted to urge said brake members longitudinally towards each other for frictional engagement with said band and the side walls of said channel member, rockable means carried by the other of said brake members and engageable with said receiving member for longitudinally separating said brake members to thereby permit longitudinal movement of said channel member relative to said receiving member, means on said channel member adjacent one end thereof adapted to engage said rockable means for rocking the latter into engagement with said receiving member thereby effecting longitudinal separation of the brake members, and means on said channel member adjacent the other end thereof adapted to engage said rockable means for freeing the latter from said receiving member to permit said spring means to urge said brake members longitudinally towards each other.

2. A position adjusting device for a pair of relatively movable parts comprising an elongated channel member adapted to be connected to one of said parts, a receiving member slidably receiving said channel member and adapted to be connected to the other of said parts, an elongated brake band disposed in said channel member and having the ends thereof secured to the opposite side walls of said channel member, a pair of oppositely disposed wedge shaped brake members in said channel member with said band

disposed between the inclined confronting surfaces thereof, means on one of said brake members extending through said receiving member for securing said one brake member relative to the latter, spring means connected at the opposite ends thereof to said brake members and adapted to urge the latter longitudinally together for frictional engagement with said band and the opposite side walls of said channel member whereby said channel member will be slidable only in one direction relative to said receiving member, a projection formed upon said receiving member, a rockable cam member carried by the other of said brake members adapted in one position thereof to engage said projection and longitudinally separate said brake members to thereby permit movement of said channel member in either direction, means on said channel member adjacent said one end thereof engageable with said cam member and adapted to rock the latter into engagement with said projection, and means on the other end of said channel member engageable with said cam member and adapted to rock the latter out of engagement with said projection.

3. In an article of furniture or the like having one part thereof swingable to an inclined position relative to another part thereof; mechanism for maintaining said one part in a selected inclined position intermediate extreme upper and lower positions comprising a pair of members slidable longitudinally relative to each other, a brake band extending along one of said members and having the opposite ends thereof secured to the latter, a pair of brake members on opposite sides of said band, spring means connecting said brake members and adapted to urge said brake members together into frictional engagement with said band and said one slideable member, one of said brake members being secured to the other of said relatively slideable members, a rockable brake releasing member carried by the other of said brake members and engageable with said other relatively slideable member in one rocked position for separating said brake members, and means on said one of said relatively slideable members adjacent the opposite ends thereof engageable with said brake releasing member for rocking the latter into brake setting and brake releasing position, respectively.

4. In an article of furniture or the like having one part thereof swingable to an inclined position relative to another part thereof; mechanism for maintaining said one part in a selected inclined position intermediate extreme upper and lower positions comprising an elongated channel member, hinge means on one end of said channel member for connection to said one part, a receiving member slidably receiving said channel member and having hinge means thereon for connection to said other part, a brake band disposed in said channel member and extending the length thereof, means fixing the opposite ends of said band to the opposite side walls of said channel member, a pair of oppositely disposed wedge shaped brake members in said channel member on opposite sides of said band, spring means connecting said brake members and adapted to urge the latter together for frictional engagement with said band and the side walls of said channel member, means on one of said brake members connecting said one brake member to said receiving member, a projection on said receiving member, a cam mem-

ber rockably carried by the other of said brake members and adapted to engage said projection for separating said brake members to permit movement of said channel member in either direction, an arm extending from said cam member, and a stop on said channel member adjacent the other end thereof and engageable with said arm for rocking said cam member into engagement with said projection for separating said brake members, said hinge means on said channel member being engageable with said arm for rocking said cam member out of engagement with said projection.
